UNITED STATES PATENT OFFICE.

JULIUS HANSEN, OF COFFEYVILLE, KANSAS.

AGITATOR FOR TREATING MINERAL OILS.

1,215,526.

Specification of Letters Patent. Patented Feb. 13, 1917.

Application filed June 3, 1916. Serial No. 101,594.

To all whom it may concern:

Be it known that I, JULIUS HANSEN, a citizen of the United States, residing at Coffeyville, in the county of Montgomery and State of Kansas, have invented certain new and useful Improvements in Agitators for Treating Mineral Oils, of which the following is a specification, reference being had to the accompanying drawings.

This invention relates to certain improvements in methods of treating mineral oils and it is an object of the invention to provide a novel and improved method for breaking or cracking heavy oil into lighter oil.

It is also an object of the invention to provide a novel and improved method wherein kaolinite is mixed with the heavy oil when within the still and wherein scraping means is employed for the proper handling of the kaolinite and to prevent coking of the still.

The novel features of the invention will hereinafter be definitely claimed.

In order that my invention may be the better understood, I will now proceed to describe the same with reference to the accompanying drawings, wherein—

Figure 1 is a view partly in elevation and partly in vertical section illustrating a still having arranged therein scrapers constructed in accordance with an embodiment of my invention;

Fig. 2 is a transverse vertical sectional view taken through the device as disclosed in Fig. 1;

Fig. 3 is an enlarged fragmentary view partly in top plan and partly in section illustrating a scraping blade as herein set forth; and

Fig. 4 is a view partly in section and partly in side elevation of the details illustrated in Fig. 3.

As disclosed in the accompanying drawings, S denotes a still which is adapted to contain the mineral oil to be treated, said still comprising a horizontally disposed cylindrical container supported in a conventional manner and having disposed through its axial center the shaft 1 rotatably supported by the bearings 2 and disposed through the glands 3 for a purpose which is believed to be self-evident. The shaft 1 is also provided, as at 4, with means whereby the requisite rotation may be imparted to the shaft.

Radiating from the shaft 1 within the

still S and adjacent the heads thereof, are the arms 5, the longitudinally alined arms being connected at predetermined points inwardly of their outer or free ends by the stationary shafts or rods 6.

B denotes a plurality of blades provided adjacent their ends with the rearwardly directed tails 7 rotatably engaged with a shaft or rod 6 and having their free ends bifurcated, as at 8, in order to straddle the adjacent longitudinal marginal portion of the strip 9 interposed between each pair of longitudinally alined arms 5 whereby it will be perceived that the blades B are effectively held against back-thrust during the rotation of the shaft 1.

The blades B are angularly disposed relative to their coacting arms 5 and such angle is determined by the relative positions of the intimate shafts or rods 6 and strips 9.

The blades B are adapted to contact with and have scraping action upon the inner face of the side wall of the still S in order to prevent coke from adhering to the still bottom.

It is also a purpose of my invention to deposit within the still S a predetermined quantity of fullers'-earth in order to effect a breaking or cracking of heavy oil into lighter oil. It has been fully demonstrated in actual practice that with the use of fullers'-earth, it is essential that a scraping means for the purpose hereinbefore set forth, be used as the rotation of the scraping elements serve to facilitate the action of the fullers'-earth and also prevents the coke from adhering to the inner surface of the still or more particularly the bottom thereof, and which would otherwise result in the burning out of the still bottom.

With my improved method I have made ten consecutive runs on 19 gravity oil and run off from 92% to 98% of 39 to 40 gravity oil from each charge and on opening the still I found the still bottom as clean as when I started. The advantages and effectiveness of my improved method are thought to be fully established by this fact.

From the foregoing description, it is thought that a method of treating mineral oils in accordance with an embodiment of my invention is of an extremely simple and comparatively inexpensive nature and is particularly well adapted for use by reason of the effectiveness of the action upon the oil together with the condition in which the

still is maintained, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice, except as hereinafter claimed.

10 I claim:

In combination with a container cylindrical in cross section, a rotatable shaft disposed through the still at its axial center, 15 arms radiating from the shaft and posi-

tioned within the container adjacent opposite ends thereof, a rod connecting longitudinally alined arms, a scraping blade pivotally engaged with the rod, a member connecting said longitudinally alined arms at 20 a point inwardly of the rod, said blade being provided with a tail having a bifurcated extremity bridging the member whereby the blade is held against back-thrust.

In testimony whereof I hereunto affix my 25 signature in the presence of two witnesses.

JULIUS HANSEN.

Witnesses:

CLYDE A. KING,
THOS. F. CASEY.
